SPINNING OR TWISTING SPINDLE WITH A DEAD SPINDLE SHANK

Johann Jacob Keyser, Grabenallee 16, Aarau, Switzerland

Filed May 19, 1961, Ser. No. 111,226

Claims priority, application Germany May 25, 1960
8 Claims. (Cl. 57—130)

The present invention relates to a spinning or a twisting spindle with a dead spindle shank which has journalled thereon two rotors for supporting the lower and the upper spindle sleeve end, the rotor receiving the lower spindle end being adapted to be driven.

An increase in the output of spinning or twisting machines causes the occurrence of a number of problems. The adaptability of a spinning or twisting machine to a wide range of different spinning materials and to a wide range of yarn numbers to be produced requires the adaptation of the creel, the driving mechanism of the main drive, of the spindle drive, and of the spindle. With regard to the creel, the driving mechanism, the main drive and in part also the spindle drive, the problems involved have been solved at least to a certain extent, but problems concerning the spindle itself have not yet been satisfactorily solved so as to allow an adaptation thereof to a wide range of spinning materials and yarn numbers.

The spindles heretofore known are generally applicable within a rather limited working range only, and this is due to their dimensions and the damping devices associated therewith. Therefore, while it is possible to universally employ a spinning machine with its creel, driving mechanism and main drive, the spindle itself permits its employment only within a rather narrow range with regard to a variation in the speed, a variation as to its length and also a variation as to the weight of the cop. If it is desired to exceed such a range, it is required to exchange all the spindles for other spindles which will be suitable for the new conditions of operation. In addition thereto, the output of a spinning machine depends on the relationship between running times and periods of stoppage, which relationship becomes more favorable when the yarn body is increased. The increase of the yarn body or cop, however, automatically makes the withdrawal of the increased yarn body more difficult so that the time of stoppage required for the withdrawal of the yarn body cannot be reduced but is rather lengthened. The relationship between running time and period of stoppage can, therefore, not be varied to the desired extent. A change of these values to the desired extent can be obtained only when, on one hand, the spindle itself is adaptable to a wide range of materials to be processed and a wide range of yarn numbers. However, simultaneously with the increase in the yarn body, it is also necessary to facilitate the withdrawal operation of the yarn body. It is only the solution of this important problem, namely, the creation of a universally employable spindle, which will yield a favorable relationship between production times and periods of stand still and which thus will be able to increase the output of spinning or twisting machines.

It is, therefore, an object of the present invention to provide a spinning or twisting spindle which will overcome the above mentioned difficulties.

It is another object of this invention to provide a universally applicable spindle which will make it possible greatly to increase the range of applicable yarn bodies and yarn numbers.

These and other objects and advantages of the invention will appear more clearly from the following specification in connection with the accompanying drawings, in which:

2

FIG. 1 illustrates a spinning or twisting spindle according to the invention with a short sleeve.

FIGURE 1a illustrates the uppermost portion of FIGURE 1 but on a considerably larger scale than FIGURE 1.

FIG. 2 represents a spinning or twisting spindle according to FIG. 1 but with a long sleeve.

FIG. 3 is a modified spinning or twisting spindle which is longitudinally adjustable.

FIGS. 4 and 5 respectively illustrate in two different positions a spinning or twisting spindle with adjustable long shank.

FIG. 6 is a spinning or twisting spindle with a hollow lower rotor.

FIG. 7 shows a spinning or twisting spindle of FIG. 6 with downwardly moving inner long shank.

FIG. 8 shows on an enlarged scale the support of a sleeve in the hollow lower rotor prior to the mounting of the sleeve, and

FIG. 9 shows the mounting of FIG. 8 in the hollow lower rotor.

The invention concerns a spinning or twisting spindle with dead spindle shank on which two rotors are journalled for supporting the lower and the upper end of the spindle sleeve. Of these two rotors, that rotor which supports the lower sleeve end is adapted to be driven and is in conformity with the present invention so designed that the dead spindle shank is composed of two individual shank sections which are supported coaxially independently of each other and on which independently of each other each rotor is journalled.

The term "spindle sleeves" as it applies to the present invention also comprises any type of yarn carriers which may be employed in the manner of the heretofore known spindle sleeves, in other words, all yarn bodies with yarn carrier functions. Spindle parts and spindle sleeve when assembled form the spindle body with the customary spindle function.

More specifically, according to the present invention, one of the two shank sections may with radial play embrace the other shank section and move only that end thereof which faces the other shank section journalled coaxially but independently of the other shank section. Independent journalling of the two shank sections brings about a considerable simplification in the journalling arrangement and has the advantage that the rotating sleeve adjusts itself automatically and independently of the journalling of the shank sections connected thereby to a certain axis of rotation corresponding to the rotating masses with the result that the bearings will be under completely uniform load. The sleeve may be able to carry out a pendulum movement to a certain extent as a requirement for an automatic adjustment to an axis of rotation which coincides with the axis of gravity of all rotating parts including the spinning sleeve.

Furthermore, according to a further feature of the invention, one of the shank sections may be designed as outer hollow shaft which is stationarily held on the spindle rail, said spindle rail carrying the rotor for supporting the lower sleeve. The other shank portion is designed as inner longitudinal shank, the upper end of which carries the upper end of the rotor for supporting the upper sleeve end.

The said inner longitudinal shank extends coaxially through the outer hollow shank, and the spindle rail is journalled below said spindle sleeve.

The subdivision of the carrier for a spindle sleeve in two shank sections which are journalled independently of each other in a coaxial manner and which are connected to each other along a closed path by the spinning sleeve itself, and of which at least one rotor is adapted to be driven, yields a number of further advantages. One

of these advantages is realized due to the fact that the inner longitudinal shank is, in conformity with the invention, adjustable to different sleeve lengths so that the two shank sections, without any change in construction, may be employed for various sleeve lengths.

According to a further feature of the present invention, the inner longitudinal shank may have its lower end axially displaceably journaled which feature will be of importance whenever the inner longitudinal shank constitutes the stationary shank portion, the free end of which only carries a rotatably journaled rotor as supporting body for the sleeve.

The axially displaceable support for the inner longitudinal shank may be obtained by having the inner longitudinal shank with its lower end movable into a plurality of positions into a holding bushing mounted on the bottom side of the spindle rail, while locks or like arresting means are provided for arresting said inner longitudinal shank in its respective position. Another type of adjustment may be obtained by having at least the lower end of the inner longitudinal shank provided with a thread engaged by an adjusting nut which is operable independently of the spindle rail.

Finally, it is possible, by means of nuts, to fasten the inner longitudinal shank in an axially adjustable manner to an adjusting rail independently of the spindle rail.

According to a further feature of the invention, the inner longitudinal shanks of a plurality of spinning sleeves may have their lower ends connected to a common rail independently of the spindle rail, which common rail is adjustable as to height so that, by lifting or lowering said common rail, an entire spindle row may be adjusted as to different sleeve lengths. Such an arrangement has the advantage that, by lowering the said rail, the inner longitudinal shank may be lowered to such an extent that the mounted sleeves for purposes of removal will not any longer have to be displaced upwardly in a longitudinal direction over the inner longitudinal shank in order then to be removed. It is rather sufficient to lower the inner longitudinal shank so that the sleeve will become free from the lower rotor merely by tilting. Correspondingly, also, the mounting of new sleeves will be considerably simplified because they have to be slipped over the remaining short end of the inner longitudinal shank only. Their proper location and holding will be effected automatically when the inner longitudinal shank is moved upwardly to such an extent that the free sleeve end engages the inner longitudinal shank, whereas the other sleeve end will be held fast by the lower rotor.

The last mentioned arrangement may furthermore be improved by making the inner longitudinal shank nearly or completely movable downwardly out of the outer hollow shank.

According to a further development of the invention, the inner diameter of the outer hollow shank corresponds at least to the maximum diameter of the spinning sleeve while said spinning sleeve together with the inner longitudinal shank is movable from below into the outer hollow shank. In this way, new sleeves may be moved in from below so that slipping on of new sleeves may be directly combined with the removal of the cops. When the inner longitudinal shank is moved outwardly in downward direction, the cop will be freed from the inner longitudinal shank and may be tilted laterally directly from the lower rotor without the necessity of being lifted off. This in itself represents a great advantage because such lifting off requires considerable force when large cops are involved and, thus, represents a time-consuming and cumbersome operation. Inasmuch as with the tilting off simultaneously also the inner longitudinal shank is moved downwardly where it will be free, it is possible simultaneously to mount a new sleeve which will then move into its working position from below. In its moved-in position the new sleeve will engage the lower rotor so that both sleeve ends will be supported. In this connection, it is immaterial whether the sleeve is rotated by a

rotating and driven lower rotor or whether a second longitudinal shank is driven and rotates the lower rotor through the intervention of the sleeve.

The subdivision of the support for the spinning sleeve into two shank portions, namely, into an outer hollow shank and an inner longitudinal shank brings about further advantages, particularly when the inner longitudinal shank is supported by an adjustable rail adapted to be lowered.

As is well known, the rotor supporting the lower sleeve end may be driven so that the other rotor will be rotated merely by the spinning sleeve connected thereto.

However, also in reverse manner, an inner longitudinal shank designed as a rotor may be driven so that the lower rotor which is freely rotatably journaled on the spindle rail may be rotated through the intervention of the mounted sleeve. In this way, the diameters of the individual bearings will be kept relatively short so that relatively lower circumferential speeds will occur even if the speed of the spindle is very high.

Referring now to the drawings, the same reference numerals are applied to the same parts throughout the various figures. The various arrangements shown in the drawings substantially comprise a spindle rail 1, spinning sleeves 2, 2', a brake lever 3 for braking the spindle and thereby the sleeve, a brake nut 4 and a counter brake nut 5. The spindle comprises the outer hollow shank 6 with the running sleeve 7 of the whorl. The lower whorl board is designated with the reference numeral 8, whereas the reference numerals 9 and 9' designate the upper whorl board between which there is located the running sleeve 7 of the whorl. The whorl is journaled in anti-friction bearings 10. Sleeves 2, 2' have their lower end supported by the rotatable supporting members 11, 12, 12'. The reference numeral 13 designates a spring ring disc and the reference numeral 14 designates a hollow shaft nut. All figures comprise the above mentioned elements.

Referring more specifically to the embodiment of FIGS. 1 and 2, it will be noticed that the outer hollow shank 6 extends through an opening in the spindle rail 1. The free end of hollow shaft 6 has mounted thereon below the spindle rail 1 the above mentioned spring ring disc 13 and nut 14 threadedly engaging said free end of hollow shaft 6. The said spring disc 13 and nut 14 are tightened against the brake nut 4 thereby properly and unequivocally locating the hollow shaft 6. The free end of hollow shaft 6 has furthermore screwed thereon a bushing 15 which is closed at the bottom and the interior of which is provided with annular grooves 16 having mounted therein rings 17 of elastic material. The said rings 17 extend around the lower end of bar 18 which is provided with threads or annular grooves, said bar 18 forming the inner longitudinal shank. The employment of elastic rings 17 makes possible a certain lateral deviation of the lower end of the inner longitudinal shank 18 so that said inner longitudinal shank will be able automatically to adjust its axis to the line of gravity of all parts rotating therewith. Directly adjacent to the lower end of the hollow shank 6 there is a spring ring 19 which, similar to the rings 17, engages an annular groove 20 or the thread of the inner longitudinal shank 18. In this way, the location of the inner longitudinal shank is clearly determined as to height and may be adjusted as indicated in FIG. 2. Due to the possibility of changing the position of the inner longitudinal shank 18 as to height, sleeves of different lengths may be employed. Thus, FIG. 1 shows a short sleeve 2, whereas FIG. 2 shows mounted on the spindle a long sleeve 2'. The upper end of the inner longitudinal shank 18 has arranged thereon a sleeve supporting body 21 which forms a rotor and is freely rotatable. To this end, referring to FIG. 1a, the sleeve supporting body 21 comprises a central pin 22 with head 23 which pin is axially inwardly directed. Pin 22 extends through bore 24 of a bushing 25 mounted on the end of the inner longitudinal shank 18 and thereby is secured

against withdrawal. The nozzle-shaped cross section of bore 24 will within certain limits permit pendulum movements of the rotatable sleeve supporting body or member 21. The axial pressure which is effective through the intervention of the supporting member 21 and sleeve 2, 2' is absorbed by the supporting plate 26 provided with a spherical surface. The lower end of the spinning sleeve 2, 2' rests on the rotatable supporting body or member 11 the outer surface of which is slightly anchored so as to allow an automatic adjustment of the spinning sleeve 2, 2' in conformity with the line of gravity. For compensating differences in dimensions of sleeve 2, 2' or member 11, and to aid member 11 in conveying its rotational movement upon the spinning sleeve, for instance one or more sleeve couplings 27 may be employed which will not affect the withdrawal of sleeve 2, 2'. Such coupling 27 comprises a spring-urged ball which, while being located in a cavity in member 11, slightly protrudes outwardly beyond the periphery of member 11 and is pressed against sleeve 2, 2'.

As will be evident from the drawings, the inner longitudinal shank 18 extends with radial play through the hollow shank 6. The inner longitudinal shank 18 is supported in sleeve 15 merely by the spring ring 19 and the elastic ring 17. The inner longitudinal shank 18 is furthermore supported at its outer free end by means of the spinning sleeve 2, 2' through the intervention of the rotatable sleeve supporting member 21, said spinning sleeve representing the only connection between the inner longitudinal shank 18 and the lower rotating member. The said lower rotating member is formed by the rotatable whorl elements 7, 8 and 9 in combination with supporting member 11 and carried thereby.

As to the raising and lowering of shank or spindle 18, it will be appreciated that this is effected manually as far as the embodiment of FIGS. 1 and 2 is concerned. However, with the embodiment of FIG. 3, this raising and lowering action is effected by a worm 37 and worm wheel 30 which latter forms the spindle nut for the thread 29. With the embodiment of FIGS. 4 to 7, the said raising and lowering action is effected by raising and lowering rail 53.

Aside from the fact that the spinning or twisting spindles according to the illustrated embodiment may thus be used for spinning sleeves of different lengths, it will, due to the way in which it is journaled, bring about the advantage that the sleeve will be able during its rotation, without difficulty, to adjust its axis automatically with regard to the line of gravity of all rotating parts. As a result, a considerably higher speed may be selected than is obtainable with the heretofore known spindle bearings. This is furthermore aided by the fact that the mass of the rotating spindle parts is considerably less than that of the heretofore known spindles. The reduction in weight of the rotating parts will, particularly with spindles for large cops be of particular importance.

According to the embodiment of FIG. 3, the inner longitudinal shank and the lower rotating member are nearly of the same construction as with the embodiment according to FIGS. 1 and 2. The difference between the arrangement of FIG. 3 and that of FIGS. 1 and 2 consists primarily in the design of the upper whorl board 9' which consists of one piece with the rotatable supporting member 12. The said rotatable member 12 represents a hollow body open at the top and surrounding the lower end of sleeve 2 while serving simultaneously as winding-on cup. An elastic hollow ring 28 is interposed between member 12 and sleeve 2 and serves as a sleeve coupling. This sleeve coupling coupling sleeve 2 to member 12 also furnishes the possibility of causing the spinning sleeve 2 during its rotation automatically to adjust itself as to the line of gravity of all rotating parts.

The lower end of the longitudinal shank 18 is below the spindle rail 1 provided with an adjusting thread 29. The thread 29 is engaged by a nut 30 designed as worm wheel

5 which by means of its hubs 31 and anti-friction bearings 32 is journaled in the adjusting rail 33. A uniform distance between spindle rail 1 and adjusting rail 33 is assured by sleeve 34 which surrounds the inner longitudinal shank 18 below the spindle rail 1 and by means of its upper end rests on a collar 35 of nut 14. The lower end 36 of sleeve 34 rests in the supporting member 33. The worm wheel 30 meshes with worm 37. By rotating worm 37, the worm wheel 30 is rotated whereby the inner longitudinal shank 18 is rotated so that said shank 18 will move axially in one or the other direction. This furnishes the possibility of varying the axial length of the inner longitudinal shank 18 above the spindle rail 1 and thereby makes it possible to adjust the axial length of shank 18 in conformity with the length of the respective employed sleeve 2.

With the embodiment according to FIGS. 4 and 5, those parts which are arranged above the spindle rail 1 correspond to the parts according to FIGS. 1 and 2.

20 Below the spindle rail, there is provided an adjustable rail 53 which is adjustable to different heights. Fixedly connected to rail 53 is the lower end of the inner longitudinal shank 18. This connection is effected by means of the thread 54 and nuts 55. According to FIG. 4, the inner longitudinal shank 18 occupies its moved-out position, the spindle sleeve 2 having its lower end on the rotatable supporting member 11. The upper end of spindle sleeve 2 rests on the sleeve supporting member 21. The sleeve supporting member 21 is rotatably mounted on the inner longitudinal shank 18. If the lower rotatable supporting member is driven through the intervention of the running sleeve 7 of the whorl, also sleeve 2 will be rotated which in its turn causes the sleeve supporting member 21 to rotate. Thus, the spindle sleeve 2 forms the driving connection between the sleeve supporting member and the lower rotatable supporting member.

According to the arrangement of FIG. 5, the inner longitudinal shank 18 is due to a lowering of the adjusting rail 53 lowered to such an extent that the sleeve supporting body 21 of the inner longitudinal shank 18 rests upon the rotatable supporting member 11. In this position, the spindle sleeve 2 may be mounted without any difficulties and may also at the end of the spinning operation, when the cop is wound onto the spinning sleeve, be withdrawn merely by lateral tilting. This means a considerable simplification of the handling because it is not necessary any longer to move the heavy cop weight upwardly over a long sturdy sleeve and to remove the cop weight over said sleeve.

FIGS. 6 and 7 illustrate an embodiment which differs from the embodiments described so far in that the inner diameter of the outer hollow shank 6 permits a play-free passage of a sleeve 2. Aside from the fact that the diameter values of the parts of the lower supporting members are different, there are provided the brake lever 3, the braking nut 4, the braking counter nut 5, the running sleeve 7 of the whorl, the lower whorl board 8, the two whorl anti-friction bearings 10, the spring ring disc 13 and the hollow shank nut 14. The upper whorl board 9 consists of one piece with the sleeve supporting member 12' in which the lower end of sleeve 2 may rest through an elastic hollow ring 28. The inner longitudinal shank 18" is designed as a hollow tube which by means of a thread and nuts 55 is firmly connected to the adjusting rail 53. The other end of the hollow inner longitudinal shank 18" supports the conical sleeve carrier 57 through the intervention of the anti-friction members 56. The lower end of sleeve carrier 57 is radially supported in the interior of the sleeve supporting member 12' by an elastic hollow ring 28 when the inner longitudinal shank 18" has in conformity with FIG. 6 passed through the outer hollow shank. The outer upper end of the inner longitudinal shank 18" together with the conical hollow supporting shank 18" is provided with a cover disc 58.

As will be evident from FIG. 7, the inner longitudinal

member 57 carried thereby may be lowered downwardly so that the spinning sleeve 2 with the cops 59 thereon may be removed by lateral tilting. Thereupon, a new sleeve 2 can be mounted in a very simple manner, and the inner longitudinal shank with the sleeve carrier may be moved into the position shown in FIG. 6. It is, however, also possible to move the inner longitudinal shank 18" completely downwardly and to place the spinning sleeve 2 below the spindle rail 1 upon the inner longitudinal shank and then to move said spinning sleeve 2 into the position shown in FIG. 6. In this way, there is created the possibility of combining with the tilting off of spinning sleeve 2 with cop 59, a mounting of a new spinning sleeve 2 on the inner longitudinal shank in lowered condition so that the removal of the cops and the introduction of a new spinning sleeve may follow each other directly which fact means a considerable saving in time.

In addition thereto, there is created the possibility of ascertaining the weight of the cop without having to remove the spinning sleeve with the cop from the machine. To this end, it is merely necessary to design the adjusting rail 53 as a balance or a scale beam. If first spinning sleeve 2 is mounted on the hollow sleeve body 57, the spinning sleeve 2 is moved through the outer hollow shaft to such an extent that the spinning sleeve will not engage the lower rotatable supporting body. Thereupon, the sleeve weight is ascertained or determined. Subsequently, the inner longitudinal shank is lowered to such an extent that the spinning sleeve 2 moves into the position of FIG. 6. In this position a spinning operation may be carried out until the cop 59 has been formed. Following the completion of the spinning operation, the adjusting rail 53 together with the inner longitudinal shank 18" and the spinning sleeve 2 with cop 59 is moved upwardly to such an extent that the spinning sleeve 2 will separate from the lower rotatable supporting member namely from the elastic ring 28 and the rotatable supporting member 12'. By means of the adjusting rail 53 which is designed as scale or balance arm, the total weight will then be ascertained so that the difference of this weighing operation and the first weighing operation will determine the cop weight proper. Subsequently, the cop 59 with spinning sleeve 2 is tilted off, and a new spinning sleeve 2 is moved in through the outer hollow shank.

FIGS. 8 and 9 illustrate in detail and on an enlarged scale the design of the hollow elastic ring 28 by means of which the spinning sleeve 2 or the hollow spinning sleeve carrier 57 is supported in the rotatable supporting member 12'. FIG. 8 illustrates the supporting member 57 prior to the insertion of the spinning sleeve 2 while FIG. 9 illustrates the supporting member 57 after the insertion of the spinning sleeve 2. In the last mentioned instance its cross section is deformed in an oval manner. It thus brings about a tolerance compensation and assures the rotation while acting in the manner of a ball joint so that the rotating spinning sleeve 2 is able automatically to adjust itself in conformity with the line of gravity of all rotating individual elements. These hollow rings may, of course, also be replaced by spiral springs or similar spring elements.

It is, of course, to be understood that the present invention is, by no means, limited to the particular constructions shown in the drawings but also comprises any modifications within the scope of the appended claims.

What I claim is:

1. A mounting for spinning and twisting spindles, which includes: a spindle rail, a spindle extending through said spindle rail and comprising two individual spindle sections coaxially arranged one within the other so that one spindle section forms an inner spindle section and the other spindle section forms an outer spindle section, holding means arranged below said spindle rail and connected thereto, the lower end of said inner spindle section extending into said holding means and being axially adjustable relative thereto, means connected to said holding

10
15

means for arresting said inner spindle section in its respective axially adjusted position, and two rotatable members respectively and independently of each other journaled on said spindle sections for supporting a spinning sleeve, one of said rotatable members being adapted drivingly to be connected to a driving means and the other one of said rotatable members being automatically variable in distance from said one rotatable member in conformity with the axial adjustment of said inner spindle section.

2. In a mounting for spinning and twisting spindles: a spindle having an inner individual and normally stationary spindle section and an outer individual spindle section shorter than said inner spindle section and substantially coaxial therewith, at least the lower end of said inner spindle section being provided with a thread, adjusting means engageable with the thread of said inner spindle section and being operable selectively to engage different thread positions of said inner spindle section for selectively axially adjusting said inner spindle section, and two rotatable members respectively and independently of each other journaled on said spindle sections for supporting a spinning sleeve, one of said rotatable members being adapted drivingly to be connected to driving means.

3. In a mounting for spinning and twisting spindles: a spindle having an inner individual spindle section and an outer shorter individual spindle section independent of said inner spindle section and substantially coaxially arranged thereto, a spindle rail, the lower end of said inner spindle section axially adjustably extending through said spindle rail, two rotatable members respectively and independently of each other journaled on said spindle sections for supporting a spinning sleeve, one of said rotatable members being adapted drivingly to be connected to driving means, and adjustable rail means independent of said spindle rail and adjustable in axial direction of said inner spindle section, said adjustable rail means having the lower end of said inner spindle section connected thereto.

4. In a textile machine having a spindle rail and a plurality of spindles: each of said spindles comprising an outer spindle section mounted on said spindle rail and an inner spindle section longer than said outer spindle section and substantially coaxial therewith, said inner spindle section extending through said spindle rail, an adjusting rail arranged below said spindle rail and adjustable in the axial direction of said inner spindle sections, at least some of said inner spindle sections having their lower ends connected to said adjusting rail, said adjusting rail being movable independently of each spindle rail, and a pair of rotatable members respectively journaled on each of said spindle sections pertaining to the respective spindle for supporting a spinning sleeve, one of said rotatable members of each pair of rotatable members being mounted on the respective inner spindle section and the other one of said rotatable members of each pair of rotatable member being mounted on the respective outer spindle section, one of said rotatable members of each pair of rotatable members being adapted drivingly to be connected to driving means.

5. In a mounting for spinning and twisting spindles: a spindle having an inner individual spindle section and an outer individual spindle section shorter than said inner spindle section and substantially coaxially arranged thereto, means supporting said spindle sections independently of each other, said inner spindle section selectively being

65 at least nearly movable out of said outer spindle section when being moved in downward direction, and two rotatable member respectively and independently of each other journaled on said spindle sections for supporting a spinning sleeve, one of said rotatable members being adapted drivingly to be connected to driving means.

6. In a mounting for spinning and twisting spindles: a spindle having an individual hollow outer spindle section and an individual inner spindle section substantially coaxial with said outer spindle section and longer than the latter, means supporting said shank sections independently

70
75

of each other, said inner spindle section being adapted to receive and support a spinning sleeve, said outer spindle section having an inner diameter corresponding at least to the maximum diameter of a spinning sleeve to be supported by said inner spindle section, said inner spindle section being adapted together with a spinning sleeve thereon to pass through said outer spindle section from the bottom side thereof, two rotatable members respectively and independently of each other supported by the inner and outer spindle sections, one of said rotatable members being adapted drivingly to be connected to driving means, and rotatable means for rotatably journaling a spinning sleeve on said inner spindle section.

7. A mounting for spinning and twisting spindles, which includes: a spindle rail, a spindle having two individual sections, one of said spindle sections forming an outer hollow spindle section and being fixedly connected to said spindle rail, a first rotor supported by said outer hollow spindle section for supporting the lower end portion of a spinning sleeve, a second rotor mounted on the upper end of said other spindle section for supporting the upper end portion of a spinning sleeve, said last mentioned other spindle section forming an inner longitudinal spindle section extending coaxially through said outer hollow spindle section and also extending through said spindle rail, said other spindle section being adjustable in its axial direction relative to said hollow spindle section and said spindle rail, and supporting means arranged below said spindle rail and operable to support said other

20

spindle section selectively at different levels to thereby vary the distance between said first rotor and said second rotor for mounting spinning sleeves of different length thereon.

- 5 8. A mounting for spinning and twisting spindles, which includes: a spindle having a stationary spindle section and a movable spindle section coaxially arranged with regard to each other, two rotatable members respectively and independently of each other supported by said stationary and movable spindle sections for supporting a spinning sleeve, one of said rotatable members being adapted drivingly to be connected to driving means, and first and second supporting means respectively supporting said spindle sections independently of each other, said 10 supporting means for said movable spindle section including means for selectively axially adjusting said movable spindle section with regard to said stationary spindle section to thereby selectively vary the distance between said two rotatable members.
